UNITED STATES PATENT OFFICE.

GEORGE B. PILLAR, OF MILWAUKEE, WISCONSIN.

WASHING MACHINE.

Application filed September 18, 1922. Serial No. 588,909.

To all whom it may concern:

Be it known that I, GEORGE B. PILLAR, a citizen of the United States, and resident of Milwaukee, in the county of Milwaukee and State of Wisconsin, have invented certain new and useful Improvements in Washing Machines; and I do hereby declare that the following is a full, clear, and exact description thereof.

10 My invention relates to washing machines of the type in which the clothes to be washed are placed in a rotary perforated drum thru which there is a continuous circulation of the cleansing fluid while the drum is rotated.

15 It is customary during the process of cleansing the clothes to subject them to treatment by a number of different solutions successively, such, for example, as a soapy solution, then a rinsing water and finally a bluing solution.

20 One of the principal objects of the present invention is to provide a machine in which there are a plurality of receptacles which are initially provided with the respective liquids 25 which are to be used and in which the clothes may be successively subjected to the action of the different liquids, each liquid after passing thru the clothes in the rotating drum being returned to the receptacle from which 30 it is taken.

It is also an object of the invention to provide a machine of this character with means whereby the liquid may be completely shut off between the periods of treatment while 35 the drum continues to rotate for the purpose of removing the excess moisture from the clothes and allowing it to drain back into the receptacle.

The invention consists further in certain 40 structural details and combinations of parts which will be more specifically described hereinafter in connection with the accompanying drawings and subsequently claimed.

In the drawings, 45 Figure 1 represents a vertical sectional view thru the central part of the machine, as indicated by the line 1—1 of Figure 2.

Figure 2 is a plan view of the invention.

Figure 3 is a sectional plan view taken on 50 the line 3—3 of Figure 1.

Figure 4 is a detail view of the valve adjusting mechanism.

Figure 5 is a detail view showing the relation between the pump and the valve box.

55 Figures 6, 7 and 8 are diagrammatic views showing the valve in different positions, and

the adjustment of the drain spout in connection therewith.

Referring now to the drawings in detail, the numeral 1 represents the frame structure 60 on which are supported a plurality of liquid receptacles 2, 3 and 4. These receptacles are preferably arranged in the manner shown about the center of the machine, and a central bearing block 5 supported upon 65 the frame structure rotatably supports a vertical shaft 6 which carries at its upper end, a perforated drum 7 for receiving the clothes. This drum is provided centrally with an upwardly extending sleeve thru the 70 upper end of which is secured a pin 9 which is received in the bifurcated upper end of the shaft 6 to support the drum. A disk 10 is secured to the shaft 6 near its lower end and is provided with downwardly projecting pins 11 which are received between the spokes of a wheel 12 and driven thereby. 75

The wheel 12 is journalled concentric with the shaft 6 and is provided with a bevel 80 friction face which is engaged by the bevel friction gear 13, which is secured to the shaft 14 of the motor 15. The gear 12 is held in engagement with the gear 13 by a suitable roller bearing 16.

The motor shaft 14 also has a driving connection 17 with a shaft 18 which operates a pump 19 by means of which the cleansing liquid is pumped upwardly thru the pipe 20, and projected over the clothes contained in the drum by a suitable spray head 21. The 90 liquid is drawn by the pump thru the pipe 22 from the valve box 23, thru which connection is made with either of the pipes 24, 25 or 26 by means of a rotary valve 27. The pipes 24, 25 and 26 are connected with 95 the receptacles 2, 3 and 4 respectively, and the valve 27 is mounted on a rotary shaft 28 which is adjustable by means of a hand wheel 29 to place the pump selectively in communication with either of the receptacles desired. 100

When the valve has been suitably adjusted and the motor 15 started, the drum 7 is rotated while the liquid is continuously pumped up thru the pipe 20 and sprayed over the clothes. This liquid, as it percolates thru the clothes, drains out thru the perforations in the drum 7 and collects in the circular trough 30 which is supported beneath the drum. The sides of the trough 105 are extended upwardly, as shown at 31, to surround the drum and catch the liquid 110

which is thrown outwardly by centrifugal action. The top of the trough is closed by a cover 32 which also encloses the drum. The liquid from the trough 30 drains thru 5 the outlet 33 into a spout 34 which is connected therewith by a suitable union 35. This spout 34 is angularly adjustable about the opening 33 so as to deliver into the receptacle 2, as shown in Figure 3, or into the 10 extension spout 36 which delivers to the receptacle 3 or into the extension spout 37 which delivers into the receptacle 4. The adjustment of the spout 34 is effected automatically whenever the valve 27 is adjusted 15 so that the liquid draining from the drum 7 is returned to the receptacle from which it is drawn.

The connection between the valve 27 and the spout 34, by means of which the latter is 20 automatically adjusted in coordination with the former, comprises a cam 38 which is secured to the valve shaft 28 and provided with a pair of pins 39 and 40, as shown in Figure 3. The successive adjustments of 25 the valve and the corresponding locations of the pins 39 and 40 are illustrated in Figures 6, 7 and 8. The spout, as shown, is provided with a lateral rib 41 and a finger 42, which are engaged successively by the 30 pins 39 and 40 to adjust the spout. As shown in Figure 6, the water is being drawn thru the pipe 24 from the receptacle 2, and the spout 34 is in position to deliver back into the receptacle 2. When the shaft 28, 35 which carries the valve 27 at its lower end, is rotated to open the pipe 25 to the action of the pump so as to draw the liquid from the receptacle 3, the pin 29 engages the rib 41 and moves the spout to the position shown 40 in Figure 7 so that it delivers to the spout 36, which, in turn, delivers to the receptacle 3.

Upon further rotation of the shaft 28 and valve 27, the pump is placed in communication with the pipe 26 and receptacle 4, as 45 shown in Figure 8. In this position the pin 40 has engaged the rib 41 and swung the spout 34 still further so that it delivers to the spout 37 and thence back to the receptacle 4. When the shaft 28 and valve 27 are 50 rotated still further in the same direction until they again reach the position shown in Figure 6, the pin 40 engages the finger 42 and swings the spout 34 back into the position shown in Figures 3 and 6.

From the above description, it will be seen 55 that the liquid may be drawn from any of the three receptacles and will always be returned to the receptacle from which it is drawn. The valve 27 also has an intermediate position between each of the active positions wherein the pump is shut off from all of the receptacles. This is for the purpose of permitting the drum to rotate 60 without receiving any liquid so that the

centrifugal action thereof will drain all superfluous moisture from the clothes before they are subjected to treatment by the next liquid.

It will also be observed that in order to bring about the desired coordination between the spout 34 and the valve, it is essential that the shaft 28 should always be rotated in the same direction. A ratchet 43, shown in Figure 4, is therefore provided 70 to act in cooperation with the hub of the hand wheel 29, so as to prevent the operator 75 from making a mistake in effecting the adjustment.

While I have shown my invention as 80 applied to a washing machine in which three different solutions are designed to be used, it is, of course, apparent that the structure may be modified so as to be used 85 in connection with any number of receptacles.

It will also be understood that various other modifications may be made in the minor structural details without departing 90 from the spirit of the invention as claimed.

I claim:

1. In a device of the character described, a rotatable perforated drum, a trough for receiving liquid which drains from the drum, a plurality of receptacles beneath the trough for containing liquids of different composition, an outlet pipe leading from each receptacle, a supply pipe leading to the drum, a pump operable to force the liquid from the outlet pipe through the supply pipe, a valve, means for selectively adjusting the valve to connect any one of the outlet pipes to the pump and means simultaneously adjustable to direct the liquid as it drains into the trough back to the receptacle from which it is being pumped. 100

2. In a device of the character described, a rotatable perforated drum, a trough for receiving liquid which drains from the drum, a plurality of receptacles beneath the trough for containing liquids of different composition, a pump adapted to deliver liquid to said drum, selectively adjustable means for connecting the suction end of said pump to any one of said receptacles, and means adjustable simultaneously with the first mentioned means to direct the liquid from the trough back to the receptacle from which it is being drawn. 110

3. In a device of the character described, a rotatable perforated drum, a trough for receiving liquid which drains from the drum, a plurality of receptacles below the trough, an outlet from said trough, a spout oscillatable about said outlet to deliver the liquid to any one of the receptacles, a pumping system having a selectively operable connection to draw liquid from any one of the receptacles and deliver it to the drum and means for oscillating the spout in uni- 120 125 130

son with said connection to deliver the liquid to the same receptacle from which it is being pumped.

4. In a washing machine, the combination with a revolute clothes-holding receptacle, of a plurality of containers for different fluids, means for propelling fluid into said revolute receptacle to permit the same to pass outward by centrifugal action through the clothes, a drainage receptacle for collecting the fluid passing through the clothes, and means for simultaneously connecting said fluid propelling means and drainage receptacle with any one of the several containers.

5. In a washing machine, the combination of a revolute vertically arranged spindle, a perforated clothes-holding receptacle mounted thereon, a tub enclosing said receptacle, a plurality of fluid containers arranged beneath said tub, a pump for elevating and discharging fluid within said re-

ceptacle, a drainage connection from said tub, and means for simultaneously connecting said pump and drainage connection with any one of the several containers.

6. In a washing machine, the combination with a revolute vertical spindle, of a perforated clothes receptacle mounted thereon, a tub surrounding said receptacle, a plurality of containers arranged beneath said tub, a pump for elevating fluid and discharging the same into said receptacle, a motor for revolving said spindle and for driving said pump, a drainage from said tub, and means for simultaneously placing said pump and drainage in alternative connection with each of said containers.

In testimony that I claim the foregoing I have hereunto set my hand at Milwaukee, in the county of Milwaukee and State of Wisconsin.

GEORGE B. PILLAR.
